UNITED STATES PATENT OFFICE.

RESCUE B. PAGE, OF LOS ANGELES, CALIFORNIA.

FOLDING BED.

1,852,525.

Specification of Letters Patent. Patented Sept. 14, 1920.

Application filed June 30, 1919. Serial No. 308,022.

To all whom it may concern:

Be it known that I, RESCUE B. PAGE, a citizen of the United States, residing at Los Angeles, in the county of Los Angeles and 5 State of California, have invented a new and useful Folding Bed, of which the following is a specification.

My invention relates to folding beds, being more particularly a folding bed supported on a movable platform or truck which may be moved at will to any part of the room and when not in use may be rolled into a closet or alcove where it is out of the way. Folding beds of this character have 10 not been satisfactory for the reason that the trucks or platforms upon which the same are supported are quite large due to the fact that no satisfactory means has been provided for preventing the bed from toppling over when lowered or raised, and one of the 15 principal objects of my invention is to make a folding bed of the type described having a comparatively small platform or truck for supporting the bed and a movable strut for 20 taking a part of the load from the truck during the raising and lowering operation 25 of the bed.

Another object of my invention is to provide a folding bed of the type described, of 30 simple form and construction, which may be made at relatively low cost.

Other objects and advantages will appear hereinafter from the following specification.

Referring to the drawings, which are for 35 illustrative purposes only,

Figure 1 is a side elevation of a bed embodying a form of my invention, the bed being shown in full lines in lowered position and in dotted lines in its raised or closed position.

Fig. 2 is a diagrammatic plan view partly in section illustrating the way the bed may be passed through a door into a closet.

Fig. 3 is a vertical sectional view on line 45 3—3, Fig. 1.

Fig. 4 is an end view of the foot of the bed, and

Fig. 5 is a fragmentary perspective view of a portion of the head of the bed.

11 designates a truck or platform which may be made of any suitable material, in the present instance consisting of a front board 12 and back board 13 connected at their ends by cross boards 14, the corners of

the truck being curved or rounded as indicated at 15 so that the truck may be more readily passed through a door opening such as shown at 16 in Fig. 2 of the drawing. The platform or truck 11 is supported on rollers 18 which are preferably swiveled to 50 the under side of the truck. Mounted on the under side of the truck in such a manner as to project forwardly beyond the outline of the truck are horizontally arranged guide rollers 20 for the purpose of permitting the 55 structure to be rolled against a wall as shown at 21 in Fig. 2 of the drawing where one of the rollers 20 is in engagement with the wall 22 of a closet 23.

25 designates a standard extending upwardly from the truck 11, the lower end of the standard being bent to form a foot 26 which is secured to the truck by means of suitable bolts or screws 27, there being two standards employed, one on each front corner of the truck 11. The upper ends of the standards 25 are offset as shown at 28 and have pivotally connected thereto by means of a pin 29 an arm 30 which extends rearwardly and is connected by means of a pin 30 or bolt 31 to the head of the bed 32.

Each side 33 of the head of the bed is pivotally connected by means of a pin or bolt 34 to a bracket 35, such bracket 35 being formed of a right-angled member having a 85 horizontal portion which extends forwardly and is pivotally mounted on a rod 36 to the standard 25. The rod 36 extends across between the two standards 25, being secured thereto by means of suitable nuts. The 90 brackets 35 are connected to each other by means of a head board 37 which extends across the bed and is connected to the respective brackets by means of suitable screws or bolts 38.

The bed frame consists of a cross bar 40 at the head and a cross bar 41 at the foot connected in any well known manner by means of side rails 42, any well known form of springs indicated at 43 being stretched between the cross bars 40 and 41 in the usual manner. 45 designates the foot of the bed frame which may be of any suitable construction, in the present instance being made of metal and having pivotally mounted 105 thereon legs 46. 47 designates brace bars, one at each side of the bed, the outer end of the bars being connected by means of suit-

able pins or bolts 48 to the side rails 42, the inner end of the brace bars being pivotally connected to the upper end of the bracket 35 by means of the pin or bolt 34 heretofore referred to.

50 designates a movable strut, substantially a U shaped member in form, the open ends 51 being pivotally mounted on the pins or bolts 48 to the side rails 42 and the lower or closed end 52 of the strut being provided with rollers 53 which engage the floor upon which the bed is placed. 54 designates a tie rod which extends across the strut near the open end thereof so as to provide rigidity and brace the strut. Connected to the open ends of the strut 50 are coiled tension springs 55, the rear end of the springs being connected to the cross bar 40.

The legs 46 are operated by means of rods 60 connected at one end to the legs and at the other ends to the open ends of the strut 50. 62 designates a stop which receives the head board 37 when the bed is in closed position as shown in dotted lines in Fig. 1, thereby limiting the upward movement of the bed.

It is understood that the mattress and bed clothes are placed on the springs 43 in the usual manner and that any convenient form 30 of holding means may be used for holding the same in place when the bed is in upright or closed position.

When it is desired to lower the bed from the dotted line position shown in Fig. 1 to the full line position the bed is grasped in any convenient portion and pulled outwardly, the foot of the bed swinging outwardly and downwardly and the head of the bed carried by the brackets 35 swinging 40 upwardly. As the bed is lowered the strut 50 moves outwardly on the floor and takes the weight of the bed under the tension of the springs 55, the springs 55 being so proportioned as to approximately balance 45 the weight of the bed and bed clothes so that in any position from the upright or dotted position to the lowered or full line position the movement of the bed may be stopped and the bed remain in such position without 50 being held.

As the bed is moved upward into the closed position it is understood that the strut rolls back on the floor toward the truck and acts in the same manner as during the 55 lowering operation. The movement of the strut controls the position of the legs 46 through the medium of the rods 60 so that the legs are closed or folded under the bed when the bed is in upright position and the 60 legs are in supporting position as shown in full lines in Fig. 1 when the bed is in lowered position.

During the movement of lowering the bed the head 32 swings on the brackets 35. This 65 is accomplished through the medium of the

arms 30 which movement brings the head of the bed well within the line of the truck as shown in dotted lines in Fig. 1. The head board 37 resting upon the stop 62 as heretofore referred to insures a firm seat or support for the bed when in upright or closed position as shown in dotted lines in Fig. 1.

It will be seen from the above description and drawings that a very small truck may be used and that the parts of the bed are very simple in form and operation, also few in number, further I have found that by using the movable secondary support, that is, the strut, that there is no danger of the bed toppling over during the raising or lowering of the bed.

I claim as my invention:

1. A folding bed comprising a primary support, a bed pivotally mounted on the primary support, a secondary supporting member pivotally mounted on the bed in such manner that the secondary supporting member is operated by movement of the bed to roll on the floor, and elastic means connecting said bed and said secondary member for placing a tension on the secondary member during raising and lowering of the bed to balance the weight of the bed.

2. A folding bed comprising a movable supporting member, a bed pivotally mounted on said supporting member, a secondary supporting member pivotally connected to said bed in such manner that the secondary supporting member is operated by movement of the bed to roll on the floor, and tension springs connecting said secondary member and said bed to balance the weight of the bed.

3. A folding bed comprising a movable supporting member, a bed pivotally mounted on said supporting member, a secondary supporting member pivotally connected to said bed arranged to roll on the floor, and elastic means fixed to said bed behind the pivotal axis of the bed at one end and to said secondary supporting member in front of the pivotal axis of the bed whereby the weight of the bed is balanced during the raising and lowering of the bed.

4. A folding bed comprising a truck, standards on said truck, a bed pivotally mounted on said standards, and a strut pivotally connected to said bed arranged to engage the floor, and tension springs connected to said strut in front of the pivotal axis of the bed at one end and to the bed behind the pivotal axis of the bed whereby the weight of the bed is balanced during raising and lowering the bed.

5. A folding bed comprising a truck, standards on said truck, a bed pivotally mounted on said standards, a strut pivotally connected at one end to said bed, rollers on the other end of said strut arranged to en-

gage the floor, legs pivotally mounted on the bed, and means for connecting said legs to said strut to raise and lower said legs.

6. A folding bed comprising a truck, standards on said truck, a bed pivotally mounted on said truck, a strut pivotally connected to said bed arranged to engage the floor, tension springs connected to said strut at one end and to the bed behind its pivotal point at the other end to balance the weight of the bed.

7. A folding bed comprising a truck,

means for pivotally supporting a bed on said truck, a U-shaped strut member pivotally connected at its open end to each side of the bed, rollers on the closed end of said strut member arranged to engage the floor, and tension springs connecting the legs of the strut to said bed.

In testimony whereof, I have hereunto set my hand at Los Angeles, California, this 24th day of June, 1919.

RESCUE B. PAGE.
